UNITED STATES PATENT OFFICE.

WARNER R. BUXTON, OF LONGMEADOW, MASSACHUSETTS, ASSIGNOR TO BUXTON, INCORPORATED, OF SPRINGFIELD, MASSACHUSETTS, A CORPORATION OF MASSACHUSETTS.

KEY CASE.

Application filed July 24, 1924. Serial No. 728,031.

This invention relates to improvements in cases for keys and the like and is particularly concerned with improvements in the construction of the case proper as distinguished from the key holders and the manner in which they are mounted.

This invention is also a development of the inventions disclosed in United States Letters Patents Nos. 1,443,937 and 1,498,436 granted to me on January 30, 1923, and June 17, 1924, respectively. The invention, in common with that disclosed in the first named patent, seeks to define and limit the lines of fold of the enclosing flaps. Furthermore, the invention, in common with that disclosed in the second named patent, seeks to define and limit the lines of fold of the flaps primarily at the ends of the case, leaving some freedom intermediate such ends to permit the case to bulge and accommodate the mass due to the overlapping portions of the keys at this location.

The present invention, according to one feature thereof, goes one step further and is characterized in that the case is so constructed that the effective perimeter of its enclosure is to some degree extensible at points intermediate the ends of the case, whereby to accommodate the mass due to the overlapping portions of the keys at or near the central part of the case, while the perimeter of the enclosure is maintained substantially constant adjacent such ends to minimize the chance of keys and key holders moving out of the case when the latter is closed.

According to another feature of the invention, the case is made up of two strips of flexible material, one of which forms the back of the case and one of the flaps and the other of which overlaps the back to form a reinforcing member therefor and extends beyond the latter to form the other flap.

According to another feature of the invention, the overlapped portions of the strips may be so fastened together as to afford a pocket therebetween for the reception of license and registration papers and the like.

The invention will be disclosed with reference to the accompanying drawings, in which:—

Figs. 1 and 2 are front and rear elevational views, respectively, of an open key case embodying the invention;

Fig. 3 is a top plan view thereof;

Fig. 4 is a sectional plan view taken on the line 4—4 of Fig. 2;

Figs. 5 and 6 are views taken similarly to Fig. 2 and show slight modifications of the invention; and

Figs. 7 and 8 are rear and side elevational views, respectively, of a closed and well loaded key case, illustrating the bulge in the case and the desirability for the provision for extension of the perimeter of the enclosure near the center of the case.

Referring to these drawings; the case is made up of two strips 10 and 11 of flexible material, such as leather or the like. These two strips, which are usually of equal width, are partially overlapped as indicated, in such a manner that the non-overlapping portions are extended in opposite directions and the side edges 12 of the overlapped portions lie in substantially coincident relation. The overlapped portions are then fastened together along, or adjacent to, their coincident margins, as by the stitching 13 (see Fig. 2). The result is that the strip 10 forms a back 14, to which the key holders 15 are attached as by the plate 16, such back having a foldable flap 17 and being reenforced by the overlapped portion 18 of the strip 11, the portion 18 having a foldable flap 19. The flaps 17 and 19 are foldable over the back 14 in overlapping relation and may be secured together in the usual manner by the interengageable fasteners 20.

It is to be noted that the end edge 21 of each strip is unsecured to the other strip and it is this arrangement which permits extension of the perimeter of the key enclosure afforded by the case when closed. The extensible feature may be best appreciated from a consideration of Fig. 2. If the flaps 17 and 19 are grasped adjacent the fasteners 20 and pulled in opposite directions, the end edges 21, being unsecured as described, can yield and may assume positions such as those indicated by the dot and dash lines 21'. Thus, the distance between the fasteners 20 may be increased over the normal distance illustrated and it follows that the perimeter of the enclosure may be increased, as may be necessary to accommodate the keys contained therein. The keys, suspended from key holders 15, overlap to some extent and cause

the case to bulge something in the fashion illustrated at 22 in Fig. 8, at or near the center of the case. As a matter of fact, the greatest overlap of the keys is somewhat above the center of the case, the mass being greater at this location due to the heads of the keys. In Fig. 7 the end edges 21 are shown as drawn together intermediate their ends to provide for the extension of the 10 perimeter of the key enclosure.

The lines of fold of flaps 17 and 19 are defined at opposite ends of the case and the flaps are prevented from folding along other lines which are closer together by the fastening together of the overlapped portions of strips 10 and 11. The perimeter of the key enclosure adjacent the ends of the case is therefore constant, or substantially so.

The space between the overlapped portions of strips 10 and 11 may be utilized as 20 a pocket for the reception of automobile registration and license papers or the like. For the purpose of preventing these papers from sliding out from one side of this pocket, 25 the edge 21 of strip 11 may be partially stitched near its ends to strip 10, as shown at 23. Stops are thus formed for the purpose described. At the same time, the central portion of edge 21 is free to permit extension of the perimeter of the key enclosure, substantially as above described. The flap 19 when folded closes the other side of 30 the pocket.

A pocket which can be completely closed, 35 may be provided without interfering with the extension of the flaps, as shown in Fig. 4. A strip 25, of thin, soft lining leather, is doubled over, as shown, and inserted in the space between the overlapped portions 14 and 18 to form a pocket. The folded strip 40 25 will be held at its ends by the stitchings 13 and its other free edges are stitched, one to portion 18 and the other to portion 14. The flap 19 serves to close this pocket, when 45 the key case is closed.

If the extension of the flaps is not desired and one desires to utilize the overlapped strips 10 and 11 as a simple and advantageous means of forming a pocket in a key case, then the edge 21 of strip 11 may be entirely 50 stitched to strip 10 as indicated at 26 in Fig. 5. This construction provides a desirable reenforcement for back 14 as well as affording a safe and convenient pocket.

55 The invention has been disclosed herein, in a preferred embodiment with detailed variations, for illustrative purposes, but the scope of the invention is defined by the ap-

pended claims rather than by the foregoing description.

60

What I claim is:

1. In a key case, a case made up of two pieces of flexible material partially overlapped with the corresponding side edges of the overlapping portions of each in substantially coincident relation, said overlapping portions being fastened together along the coincident side edges, and a key support secured to one of said overlapping portions.

65 2. In a key case, a case made up of two pieces of flexible material partially overlapped with the corresponding side edges of the overlapping portions of each in substantially coincident relation, said overlapping portions being fastened together along the coincident side edges, and otherwise unsecured, and key supporting means mounted on one of said overlapping portions.

70 3. In a key case, a strip of flexible material forming a back for the case and one flap, a second strip of flexible material part 80 of which is overlapped behind said back and the rest of which forms the other flap, the corresponding side edges of the overlapped portions of said strips being fastened together and the ends of said strips being free, and key supporting means mounted on said back.

75 4. In a key case, a strip of flexible material forming a back for the case and a flap 90 disposed on one side thereof and foldable relatively thereto, a second strip of foldable material overlapping said back and disposed behind it and having a flap extending beyond the opposite side of said back, a support for key holders secured to said back, said flaps being foldable in overlapping relation over the back to enclose the key holders, the side edges of the overlapping portions 95 of said strips being fastened together to 100 limit and define the lines of fold of said flaps at opposite ends of the case, the ends of said strips being free to permit extension of the effective perimeter of the case between 105 said ends.

5. A folder for key cases and the like, made up of two strips of flexible material so overlapped as to provide a double back for the key case and flaps on opposite sides thereof, said strips being so connected as to 110 permit extension of the flaps intermediate their ends, and supporting means for key holders mounted on one of said backs.

In testimony whereof I have affixed my signature.

WARNER R. BUXTON.
